CLAIM

The ornamental design for a combined set of jars and
wall mounted holder, as shown and described.

DESCRIPTION

FIG. 1 is a top perspective view of a combined set of
jars and wall mounted holder showing my new design;
FIG. 2 is an enlarged front elevational view thereof;
FIG. 3 is a reduced top plan view thereof;
FIG. 4 is a reduced bottom plan view thereof;
FIG. 5 is a reduced rear elevational view thereof;
FIG. 6 is a reduced side elevational view taken from the
left of FIG. 1;
FIG. 7 is a reduced side elevational view taken from the
right of FIG. 1.
